UNITED STATES PATENT OFFICE

PAUL H. LANGE, OF BRIDGEPORT, CONNECTICUT, ASSIGNOR TO THE MAX AMS MACHINE COMPANY, OF BRIDGEPORT, CONNECTICUT, A CORPORATION OF NEW YORK

SEAMING MECHANISM

Application filed August 7, 1929. Serial No. 384,153.

The present invention relates to sealing mechanism especially of the character employing a plurality of first-operation seaming tools and a plurality of second-operation seaming tools, and has for its main object and feature the production of a simple and compact construction of the character indicated.

In the accompanying drawings the invention is embodied in a concrete and preferred 10 construction in which:

Fig. 1 is a bottom plan view of a seamer head and associated parts embodying the invention.

Fig. 2 is a vertical sectional view through 15 the first operation seaming tools substantially on the plane of line 2—2 of Fig. 1.

Fig. 3 is a vertical sectional view, through the second operation seaming tools, substantially on the plane of line 3—3 of Fig. 1.

Fig. 4 is a vertical sectional view, through the pivotal supports of the seaming tool levers, substantially on the plane of line 4—4 of Fig. 1.

Fig. 5 is a bottom plan view of the seamer 25 cams.

Fig. 6 is a side view in elevation of the seamer head.

Fig. 7 is a bottom plan view of Fig. 6.

Fig. 8 is a detached detail view of the seaming tool, its lever and cam roll.

Fig. 9 is a detail sectional view substantially on the plane of line 9—9 of Fig. 8.

1 indicates the seamer head consisting of a disc 2 having a central sleeve portion 3, an upstanding flange 4 on its upper face and a plurality of depending members 5 below its face, said members being in spaced relation as shown. The disc is further provided with cut-away portions 6 intermediate the depending members and carried by each of the latter is a segmental bracket 7. Between each bracket and the lower face of the disc is a pivotal support 8 on which latter is mounted a seaming tool lever 9 which latter swings 40 freely between members 2 and 7. In the present instance there are four such pivotal supports and four such levers. Each of the levers carries at its free end a seaming tool or roller and two of the seaming tools are first-operation tools and two are second-op-

eration tools. An examination of the bottom plan Fig. 1, reveals the fact that the seaming rollers are circularly arranged of the seamer head as are also the pivotal supports, and that said pivotal supports and seaming rollers 55 alternate with each other circularly of the seamer head. The first-operation seaming tools are designated 10 and the second-operation tools are designated 11 from which it will be seen that the first and second-operation seaming tools alternate with each other 60 circularly of the head.

Inasmuch as each seaming tool and associated parts are, with the exceptions herein-after noted, constructed like the other seaming tools, only one of them will be described in detail. Seaming tool lever 9 is provided at one end with a bushing 12 that surrounds pivot pin 8, and at its other and free end it carries a seaming tool 10 or 11 and a cam roll 65 13 or 14. The seaming tool is rotatable and is carried by spindle 15 supported by eccentric bushing 16 which latter is adjustable by means of wrench sockets 17. 18 indicates a bolt having a cut-away portion 19 and a nut 20, and it will be understood that by loosening nut 20 the bolt will be free to move when the eccentric sleeve is adjusted, and that when said nut is brought home it will maintain the parts in the adjusted position. By 70 the adjusting means above described a very fine adjustment of the seaming roller with respect to the work can be obtained and it will be noted that this adjustment in no wise effects the position of the cam roll.

21 is a carrier on which a cam roller 13 or 14 is mounted, and it will be noted that said carrier extends through cut-away portion 6. Said carrier is attached to the seaming tool lever by means of bolt 22, and in the case of the second-operation seaming tools there is interposed between said carrier and the seaming tool lever a yielding element 23, such as rubber, so that when said second-operation seaming tool passes over the side seam of the can it may yield slightly without necessarily transmitting the strain to the cam roller.

The cam rollers are located above the upper surface of the disc of the seamer head, and 100

arranged within the confines of upstanding flange 4 are two seamer cams 24 and 25. It will be noted that these cams are in different horizontal planes and it will likewise be noted that cam rollers 13 and 14 are likewise in different planes, so that first-operation cam rollers 13 coact with first-operation seamer cam 24 and that second-operation cam rollers 14 coact with second-operation seamer cam 25.

As is customary in machines of this character, the seamer head and the seamer cams are given a relative rotating motion in any of the ways known in the art. As shown in Fig. 5 there are two active cam portions 26 for the first operation and two active cam portions 27 for the second operation. Upon producing the relative rotating motion between the seamer head and the seamer cams, it will be apparent that first-operation cam roller 13 of each of the two first-operation seaming tools engages active cam portions 26 thereby causing said first-operation seaming tools to move inwardly by reason of a swinging movement of their levers on the pivotal supports. This gives the preliminary fold to the seam as will be understood. During this period the second-operation seaming tools do not engage the work. When cam rolls 13 have passed surfaces 26, centrifugal force will act to withdraw the first-operation seaming tools and cam rolls 14 of the second-operation seaming tools now engage active cam portion 27 to thereby bring the said second-operation seaming tools against the work to complete the seaming operation. When cam rolls 14 have passed surfaces 27 the second-operation seaming tools will withdraw by means of centrifugal force and, before the first-operation seaming tools are again rendered active, the finished can is removed and another can and cover is placed in the machine. Inasmuch as there are two active cam portions 26 as well as two active cam portions 27, two first-operation seaming tools and two second-operation seaming tools, it will be understood that the relative rotating motion between the seamer head and the seamer cams is equal to one-half of a revolution during each cycle of the machine.

I claim:

1. Seaming mechanism including: a seamer head, a plurality of first-operation and a plurality of second-operation seaming tools arranged circularly of said head and in alternate relation with respect to each other, a plurality of pivotal supports, also circularly arranged of said head, the tools and supports alternating with each other, a lever mounted, near one end thereof, on each pivotal support and carrying a seaming tool at its other and free end, a cam roll also carried at said free end of each lever, and two cams to effect in-and-out movement of the seaming tools, one of said cams to coact with the cam rollers of the first-operation seaming tools and the other

to coact with the cam rollers of the second-operation seaming tools.

2. The combination with a seamer head consisting of a disc, a central sleeve, a circumferential up-standing flange above the disc, and a plurality of depending members below the disc in spaced relation, said disc having cut-away portions intermediate the depending members, of a segmental bracket carried by each depending member, a plurality of pivotally supported seaming tool levers, each mounted near one end thereof, one between each bracket and disc, seamer cams above the disc and within the upstanding flange, a seaming tool at the other and free end of each lever and below the disc, and a cam roll above the disc and connected to said free end of each lever in the plane of the cut-away portions of said discs.

3. Seaming mechanism including: a seaming tool lever pivotally supported near one end thereof, a rotatable seaming tool mounted at the other and free end of the lever, a cam roll also mounted at said free end of the lever, and an adjustable eccentric bushing associated with the seaming tool to vary its position on the lever independently of the cam roll.

4. Seaming mechanism including: a seaming tool lever pivotally supported near one end thereof, a rotatable seaming tool mounted at the other and free end of the lever, a cam roll also mounted at said free end of the lever, and a carrier for the cam roll yieldingly connected to the lever.

5. Seaming mechanism including: a seaming tool lever pivotally supported near one end thereof, a rotatable seaming tool mounted at the other and free end of the lever, a cam roll also mounted at said free end of the lever, an adjustable eccentric bushing associated with the seaming tool to vary its position on the lever independently of the cam roll, and a carrier for the cam roll yieldingly connected to the lever.

Signed at New York, in the county of New York, and state of New York this 30th day of July, 1929.

PAUL H. LANGE.
